UNITED STATES PATENT OFFICE

158,561

BROOCH OR SIMILAR ARTICLE

Victor Di Mezza, Ozone Park, N. Y., assignor to
Coro, Inc., New York, N. Y., a corporation of
New York

Application January 23, 1950, Serial No. 7,412

Term of patent 7 years

(Cl. D45—19)

To all whom it may concern:

Be it known that I, Victor Di Mezza, a citizen of the United States of America, residing in Ozone Park, county of Queens, and State of New York, have invented a new, original, and ornamental Design for a Brooch or Similar Article, of which the following is a specification, reference being had to the accompanying drawing, forming part thereof.

Fig. 1 is a plan view of a brooch or similar article, showing my new design.

Fig. 2 is an edge view thereof.

I claim:

The ornamental design for a brooch or similar article, substantially as shown.

VICTOR DI MEZZA.
